UNITED STATES PATENT OFFICE.

ROBERT HAUSDORF, OF BERLIN, GERMANY, ASSIGNOR TO ACTIEN GESELLSCHAFT FÜR ANILIN FABRIKATION, OF BERLIN, GERMANY.

PHOTOGRAPHIC ROLL-FILM.

SPECIFICATION forming part of Letters Patent No. 700,684, dated May 20, 1902.

Application filed February 28, 1900. Renewed March 19, 1902. Serial No. 98,962. (No specimens.)

To all whom it may concern:

Be it known that I, ROBERT HAUSDORF, of Berlin, in the Kingdom of Prussia, German Empire, have invented new and useful Improvements in the Production of Photographic Roll-Films; and I do hereby declare that the following is a full, clear, and exact description of the invention, which will enable others skilled in the art to which it applies to make and use the same.

In the practical use of photographic roll-films designed for insertion into and removal from cameras in daylight it is the universal custom to provide a considerable length of black paper, linen, or the like as a wrapper or covering to exclude the light from the sensitized surface of the film. This covering is always colored by means of dyestuffs. Moreover, it is bleached, glued, and contains other chemical substances, such as blanc fixe, &c. The contact of all these substances with the sensitized coating may affect the latter most injuriously by rendering it less sensitive or by destroying part of it by reduction. The covering, moreover, being in consequence of its composition more or less hygroscopic, absorbs moisture from the atmosphere and transfers it to the film, which, therefore, even after a short time, may be destroyed, the film being, as is well known, stable in a perfectly dry state only. There is another inconvenience in the covering having figures and marks printed on the back in order to indicate what section of the film is being exposed. These signs, being easily transferred to the sensitized surface by pressure, may likewise pass into the negative and spoil the prints produced therefrom. Many attempts have been made in order to avoid these drawbacks. Trials have been made to manufacture the wrappers in such a way as to avoid in the same any constituents likely to affect injuriously the sensitized film, but without success. It has further been proposed to dispense altogether with a covering and to fix

the enveloping paper only at each end of the sensitized paper. In this latter case it was necessary to mark on the film the size of the negative by means of perforations, and a mechanical apparatus had to be applied which by catching into the perforated holes indicated when a section of the film had advanced. It is evident that this arrangement is a most complicated one. Moreover, it did not warrant full security.

55 The accompanying figure illustrates a piece of film, wrapper, and coating constructed in accordance with my invention.

Now I have found that all these inconveniences can be avoided in a simple and ready manner by coating the wrapper *a*, which comes into direct contact with the sensitized surface of the film *b*, with a thin layer *c* impermeable to water. This layer will prevent injuries to the film through atmospheric moisture or through such ingredients of the covering body as might be obnoxious. It will likewise prevent the marks and figures printed on the wrapper from being transferred to the sensitized surface.

70 In order to carry out my invention, I coat the enveloping body with collodion or with such solutions of resins as after evaporation of the solvent yield a layer impermeable to water.

75 Having now described my invention and in what manner the same is to be carried out, what I claim as new is—

Photographic roll-films having a coating, impermeable to water, on the wrapper or covering which comes into direct contact with the sensitized film.

80 In witness whereof I have hereunto signed my name, this 12th day of February, 1900, in the presence of two subscribing witnesses.

85 ROBERT HAUSDORF.
